UNITED STATES PATENT OFFICE

JOHN W. PAGE, OF CHICAGO, ILLINOIS

BUCKET

Application filed January 26, 1931. Serial No. 511,393.

This invention relates to improvements in buckets and, more especially, excavating or dragging line buckets of the type shown in the drawings. The invention is here shown as applied to an excavating bucket or shovel known in the art as a "Page" bucket.

Among the features of my invention is the provision of means for strengthening such a bucket and making the same more rigid, thus prolonging the life of the same.

By the use of my invention, the upper forward corners of the bucket are very much strengthened and braced. In ordinary use, such a bucket is likely to fall on these corners, with the result that they become bent unless braced in accordance with my invention.

Other features and advantages of my invention will appear more fully as I proceed with my specification.

In those forms of devices embodying the features of my invention shown in the accompanying drawings—

Figure 1 is a view in side elevation; Fig. 2 is a view in front elevation and partly in section; Fig. 3 is a view taken as indicated by the line 3 of Fig. 1; Fig. 4 is a view taken as indicated by the line 4 of Fig. 2; Fig. 5 is a view in side elevation of a modified form; Fig. 6 is a view in front elevation and partly in section; Fig. 7 is a view taken as indicated by the line 7 of Fig. 5; Fig. 8 is a view taken as indicated by the line 8 of Fig. 6; Fig. 9 is a view in side elevation of another modified form; Fig. 10 is a view of the same in front elevation and partly in section; Fig. 11 is a fragmentary top plan view of the same; and Fig. 12 is a view taken as indicated by the line 12 of Fig. 11.

I shall first describe the form of bucket shown in Figs. 1 to 4, inclusive. As shown in the drawings, this bucket is of the open top type, the sides thereof being indicated by 10 and provided with the usual pivot supports 11. Numeral 12 indicates the forward cutting edge and 13, 13, the plates to which the two branches of the hauling line (not shown) are attached in order to haul the bucket along to fill the same.

The principal feature of my invention is the provision of a hollow or box-like arch connecting the upper forward corners of the sides of the bucket. This arch is indicated, in general, by 14. The exact details 55 of construction of the arch are not important. The feature of the invention, however, is the making of such an arch of hollow or box-like construction, thus giving the same great rigidity and strength in relation to its weight. As here shown, the arch is made of top and bottom plates 15 and 16, respectively, connected by plates 17, 17, said plates all being fastened together by angle irons 18 which may be fastened by 60 any suitable means, for example, welding.

At the base of the arch, the side of the bucket is preferably provided with a double wall, as indicated by 10^a, and the lower ends of the arch merge into this widened or double 70 side wall of the bucket. The double walls 10, 10^a may be braced by suitable partitions or web members, as indicated by the I-beams 10^b, 10^b. The rear end of the double wall 10^a is preferably slanted back to meet the 75 wall 10, as indicated by 10^c.

The arch 14, as shown, is preferably raked or slanted backwardly, and corner plates 19 may be provided for strengthening purposes.

In the modified form shown in Figs. 5 to 8, inclusive, two arches are provided, one slanting backward and the other forward, said arches being joined or connected at the top by the bridging or connecting piece 20. 80 In these figures, the two arches are indicated, in general, by 14^a and 14^b and it is to be understood that the general construction of the same resembles the arch 14 of the other form. For example, as shown in Fig. 8, the 85 arches may be formed of top and bottom plates 15^a and 16^a, respectively, and side plates 17^a, 17^a, all of said plates being fastened together by angle irons 18^a.

In the construction shown in Figs. 5 to 8, inclusive, the sides of the buckets, as indicated by 110, are likewise provided with double walls 110^a to form a thickening or a widening of the side walls at the bases of the two arches 14^a and 14^b. The lower ends 100

of these arches merge into these widened side walls.

In the form shown in Figs. 9 to 12, inclusive, a single arch 14^c is provided which 5 is likewise of box-like construction, a section thereof being shown in Fig. 12. As shown in this figure, the arch may be formed of top and bottom plates 15^b and 16^b and side plates 17^b, 17^b, all of said plates being 10 connected by angle irons 18^b.

In this form, the arch 14^c is slanted back much more than in the form shown in Figs. 1 to 4, inclusive, and the top and bottom plates 15^b and 16^b are extended rearwardly, 15 as indicated by 15^c and 16^c, to form a cover for the bucket, said plates being continued rearwardly to join the back wall 21 of the bucket.

In the form shown in Figs. 9 to 12, inclusive, the side walls are indicated by 210. 20 These side walls are likewise provided with thickened walls or double walls 210^a into which the lower ends of the arch 14^c merge.

While I have shown and described certain 25 embodiments of my invention, it is to be understood that it is capable of many modifications. Changes, therefore, in the construction and arrangement may be made without departing from the spirit and scope 30 of the invention as disclosed in the appended claims, in which it is my intention to claim all novelty inherent in my invention as broadly as permissible, in view of the prior art.

What I regard as new, and desire to secure by Letters Patent, is:

1. In combination with a bucket of the character referred to having a bottom and side walls, an arch of box-like construction extending over the top of the bucket and 40 joining the upper forward corners of the side walls, said arch slanting backwardly and a second arch extending over the top of the bucket with its lower ends joined to the sides of the bucket rearwardly of the first-mentioned arch, said second arch leaning forwardly, the tops of said arches being connected.

2. A bucket as claimed in claim 1, with the side walls thereof widened by the provision of a double wall, the lower ends of both arches merging into said widened side walls.

3. In combination with a bucket of the character referred to having a bottom and side walls, an arch of box-like construction extending over the top of the bucket and joining the upper forward corners of the side walls, said arch being slanted backwardly and provided with a plate projecting therefrom over the top of the bucket rearwardly to join the back wall of the bucket, said plate forming a cover for the bucket rearwardly of the arch.

4. In combination with a bucket of the character referred to having a bottom and

side walls, an arch of box-like construction extending over the top of the bucket and joining the upper forward corners of the side walls, said arch being slanted backwardly and provided with two plates projecting therefrom over the top of the bucket rearwardly to join the back wall of the bucket, said plates forming a cover for the bucket rearwardly of the arch.

5. In combination with a bucket of the character referred to having a bottom and double spaced side walls, an arch of box-like construction extending over the top of the bucket and joining the upper forward corners of the side walls, the lower ends of the arch merging into said double spaced side walls, the inner and outer faces of the arch being substantially flush and coextensive with the inner and outer faces of said side walls respectively.

In witness whereof, I have hereunto set my hand this 19th day of January, 1931.

JOHN W. PAGE.
